JOHN C. CARPENTER, OF HOUSTON HEIGHTS, TEXAS.

SPEED-REGULATING MECHANISM.

972,815.

Specification of Letters Patent. Patented Oct. 18, 1910.

Application filed November 22, 1909. Serial No. 529,227.

To all whom it may concern:

Be it known that I, JOHN C. CARPENTER, citizen of the United States, residing at Houston Heights, in the county of Harris and State of Texas, have invented certain new and useful Improvements in Speed-Regulating Mechanism, of which the following is a specification.

My invention relates to new and useful improvements in speed regulators and more particularly to that class of such devices as are designed to be used on the mixture throttling type of engines. An illustration of its application to a gas engine is given 15 in the accompanying drawings and described in this specification.

The object of the invention is to provide a device of the character described, by which the speed of the engine will be regulated by 20 a governor operating in connection with a floating control lever to control a motive fluid valve, to be operated thereby.

Another feature resides in the provision of a resilient connection, more particularly 25 described hereinafter, for connecting the floating control lever to either of the other three elements of the device.

With the above and other objects in view, my invention has particular relation to certain 30 novel features of construction and operation, an example of which is described in this specification and illustrated in the accompanying drawings, in which—

Figure 1 is a side elevation of the device, 35 and Fig. 2 a sectional view of the resilient connection with the springs removed.

Referring more particularly to the drawings, wherein like numerals of reference refer to similar parts in each of the figures, 40 the numeral 1 refers to a centrifugal governor of well known construction and responsive to engine speed.

The numeral 2 designates the governor stem, which is hingedly connected to one end 45 of a floating control lever 3. To the other end of this lever 3 a valve stem 4 is hingedly connected for operating motive fluid valve 5.

The numeral 6 designates a manual lever, 50 operating on fulcrum 7 and adjustable by means of quadrant 8, catch 9 and spring 10, so as to operate rod 11 through a hinge connection. This rod 11 is hingedly connected to lever 3 by means of a block 12, which has a longitudinal slot therethrough, through 55 which rod 11 slides. This rod is held in normal relation to block 12 by means of set

collars 13 and 13', disposed to press against springs 14 and 14', respectively interposed between collars 13 and 13' and block 12. This resilient mechanism may be used for 60 the connection of either the governor stem, valve stem, or rod 11 to floating control lever 3.

In the operation of my device the position of the throttle valve does not correspond to 65 the position of the manual lever, but is automatically controlled by the governor so as to admit motive fluid in proper quantity to maintain the speed indicated by the position of the manual lever. In other words, 70 the manual lever is set for speed and not for throttle opening, the governor controlling the throttle opening.

The operation of my device is as follows: 75 When the free end of manual lever 6 is raised to a position corresponding with the engine speed desired, it communicates motion to lever 3 through its resilient connection therewith. The lever 3 operates upon governor stem 2 as a fulcrum, lowers the valve stem 80 4 and opens valve 5. When the engine is started, the plane of rotation of the governor weights is raised, thus lowering the governor stem 2 and operating to close the valve 5. Any further change in the position of the governor stem will tend to open or close the valve, thus admitting the motive fluid in proper quantity to maintain a uniform speed. As the manual lever is attached 85 to lever 3 nearer to the governor stem 2 than to valve stem 4, it is evident that a movement of the manual lever or governor stem will cause a greater relative movement of the valve stem and a sensitive governor control of the valve will thus be attained. 90 With the governor stem at rest, when the manual lever is raised to its limit it operates to first open the valve and then compress the spring 14. When the engine speeds up the 95 governor stem descends and operates to first relieve the pressure on spring 14 and then to close the valve 5. If, while the engine speed is at its maximum, the manual lever 6 is lowered to its limit, it first operates to close the valve and then compress the spring 14', 100 which is then held compressed, holding the valve closed, until the engine stops. In the operation of this device, the control lever 3 operates upon the governor stem 2 and the manual rod 11, alternatively, as fulcrums, 105 in controlling the valve action, as hereinbefore described.

In constructing the resilient connection, the springs 14 and 14' must be sufficiently yielding to prevent injury to the mechanism when the valve has reached its limit of movement in either direction, and must be sufficiently rigid to overcome the weight, inertia and friction of the valve and transmit positive motion thereto. The springs may be relatively stiff and not under stress, or be relatively weak and under considerable stress.

What I claim is:

1. In a speed regulating mechanism, the combination with a governor device, a manual control device, and a device for controlling the application of power to the element whose speed is to be regulated, of an interconnecting lever connected with said governor, manual control and power controlling devices so as to operate upon the two former alternatively as fulcrums and actuate the latter, the connection of one of said devices to said lever being resilient.

2. In a speed regulating mechanism, the combination with a speed responsive device, a manual control device, and a device for controlling the application of force to the element whose speed is to be regulated, of an interconnecting device, connected with said speed responsive, manual control and force controlling devices so as to operate upon the two former alternatively, as fulcrums, and actuate the latter, the connection of one of said elements to said interconnecting device being resilient.

3. In a speed regulating mechanism, the combination with a speed responsive device, a manual control rod, and a device for controlling the application of force to the element whose speed is to be regulated, of an interconnecting device, connected with said speed responsive device, manual control rod, and force controlling device, so as to operate upon the two former alternatively, as fulcrums, and actuate the latter, the connection of one of said elements to said interconnecting device being resilient.

4. In a speed regulating mechanism, the combination with a speed responsive device, a manual control lever, and a device for controlling the application of force to the element whose speed is to be regulated, of an interconnecting device, connected with said speed responsive device, manual control lever and force controlling device so as to op-

erate upon the two former alternatively, as fulcrums, and actuate the latter, the connection of one of said elements to said interconnecting device being resilient.

5. In a speed regulating mechanism, the combination with a speed responsive device, a manual control device, and a motive fluid valve, of an interconnecting device, connected with said speed responsive device, manual control device and motive fluid valve so as to operate upon the two former alternatively, as fulcrums, and actuate the latter, the connection of one of said elements to said interconnecting device being resilient.

6. In a speed regulating mechanism, the combination with a speed responsive device, a manual control device, and a device for controlling the application of force to the element whose speed is to be regulated, of an interconnecting lever, connected with said speed responsive, manual control and force controlling devices so as to operate upon the two former alternatively, as fulcrums, and actuate the latter, the connection of one of said elements to said interconnecting lever being resilient.

7. In a speed regulating mechanism, the combination with a manual control rod and a speed responsive device, of a connecting means, connected thereto in such a manner as to operate upon them alternatively, as fulcrums, and open and close a motive fluid valve, having connection with said connecting means and to be operated thereby, the connection of one of said elements to said connecting means being resilient.

8. In a speed regulating mechanism, the combination with a speed responsive device, a motive fluid valve, and a manual control device, of an interconnecting lever, connected with said speed responsive device, motive fluid valve and manual control device so as to operate upon the speed responsive device and manual control device alternatively, as fulcrums, and control the motive fluid valve, the connection of one of said elements to said lever being resilient.

In testimony whereof I have signed my name to this specification in the presence of two subscribing witnesses.

JOHN C. CARPENTER.
